CLAIM

The ornamental design for a dog-shaped children's bedside device, as shown and described.

DESCRIPTION

FIG. 1 is a perspective view of a dog-shaped children's bedside device as viewed from the top and front.

FIG. 2 is a perspective view thereof, as viewed from the top and back.

FIG. 3 is a front profile view thereof.

FIG. 4 is a back profile view thereof.

FIG. 5 is a right side profile view thereof.

FIG. 6 is a left side profile view thereof.

FIG. 7 is a top plan view thereof; and,

FIG. 8 is a bottom plan view thereof.

The details shown in broken lines illustrate features that form no part of the claimed design.
